UNITED STATES PATENT OFFICE.

LEWIS L. SCOTT, OF ST. LOUIS, MISSOURI, ASSIGNOR TO ELECTROL, INC. OF MISSOURI,
OF ST. LOUIS, MISSOURI, A CORPORATION OF MISSOURI.

MEANS FOR MAINTAINING THE PRIME IN PUMPS.

Application filed November 16, 1923. Serial No. 675,148.

This invention relates to certain new and useful improvements applicable particularly to domestic oil burners, such as described, for example, in my pending application, 5 Serial No. 538,559 and has for its special object the provision of means for preventing the loss of prime of the oil pump used for supplying the oil to the burner.

The domestic oil burner to which my invention relates is of the non-gravity type, and, in such systems, the main fuel supply tank is usually buried underground, and fuel is lifted at distances, varying from five to ten feet in height, by a pump and delivered to the fuel nozzle of the burner, located within a suitable furnace.

In the interest of quietness, efficiency and economy in operation, it has been found desirable, if not actually necessary, to use a 20 pump of the gear type, and where this type of pump is used, it has been found that unless suitable preventive means are employed, they will lose their prime when shut down for a few hours and become, therefore, inoperative until they are again primed by some suitable means.

My invention overcomes this disadvantage by providing suitable means, operating automatically, for preserving the prime of the 30 pump for indefinite periods of time when the pump is not being operated.

Other objects of the invention relate to the construction involved, whereby the principal object of the invention is attained.

35 The invention is illustrated in the accompanying drawing, in which—

Figure 1 is a diagrammatic view, partly in elevation and partly in theoretical section, illustrating a domestic oil burning system, and the construction embodying my invention; and

Figure 2 is a plan view of a combined oil pump and blower.

Referring now to the drawing, the numeral 45 1 indicates a furnace, such as ordinarily used for heating purposes in houses, and having the usual fuel opening closed by a door 2. Mounted on this door, in any suitable manner and communicating with the interior of the furnace, is an oil burner 3, of any suitable type adapted to produce a combustion of mixed oil and air, said burner being fed with air from a duct 4, and with oil from a pipe 5. The air duct 4 communicates

with a fan casing 6; and air is forced from 55 said casing through the duct 4 by a fan 7. The duct 4 and fan casing may be supported in any suitable manner, as by means of standards 8, secured at their upper ends in brackets 9 on the sides of the outlet end of 60 the pump casing. The fan 7 is driven by a motor 10, and the shaft 11 of said motor is common to the fan 7 and to a gear pump 12.

The numeral 13 indicates the main oil supply tank, extending into which is a pipe 65 14, which communicates with the interior of the tank near the bottom thereof, and has a coupled member forming a continuation thereof, which is connected to a supply pipe 15, leading to the inlet side of the pump 70 12, in the length of which may be located a small drain reservoir 16 and a check valve 17.

In order to start the gear pump initially, it is necessary to provide a plunger pump, such 75 as indicated at 18, having a hand-operated plunger 19. This pump is of the ordinary construction and operates in connection with the check valve 17. A hand-operated valve 20 is used to open and close communication 80 between the pump and the pipe 15.

In operation, the gear pump 12 pumps an excess of fuel, that is, more than is required for the burner itself, and this excess is by-passed back to the main fuel tank 85 through a by-pass pipe 21 communicating with the pipe 5. The by-pass is regulated by a hand-operated valve 22, and by regulating this valve, the fuel pressure at the fuel nozzle within the furnace is adjusted. 90

In order to accomplish the purpose of preserving the prime in the pump 12, I provide a small tank 23 which can be anywhere from one to five gallons in capacity, and I lead the by-pass pipe 21 to this tank and connect it with the same near the bottom thereof. This tank is placed slightly above the discharge of the pump through pipe 5, as shown. From the top portion of the tank 23, an overflow pipe 24 leads back to the main fuel tank, and preferably is connected, for this purpose, to a vent pipe 25, which communicates with the top of the main fuel supply tank 13.

In operation, it will be seen that the by-passed oil discharged through pipe 21 must first fill the tank 23 to the level of the overflow pipe 24 before the oil can return to

the tank 13, and hence the auxiliary tank 23 will always be automatically maintained full of oil, or substantially so.

It will further be seen that the provision 5 of the auxiliary tank 23 will operate to always keep the pump and the fuel lines full of fuel, and will not permit air to enter, so that the pump will always preserve its prime and will be in condition to operate 10 to pump oil to the burner whenever the motor is started.

I claim:

1. In an oil burning system of the type described, involving a source of liquid fuel 15 supply, and a pump located above the fuel supply and having a suction pipe running to said fuel supply for withdrawing fuel therefrom and delivering it to a point of combustion, an auxiliary reservoir of liquid fuel 20 located above the level of the suction pipe running to the fuel supply and of the discharge outlet of said pump and communicating therewith, whereby to maintain fuel in the fuel line and pump when the latter is 25 not in operation.

2. In an oil burning system of the type described, including a fuel pump and a pipe leading therefrom to a point of combustion, a main source of liquid fuel supply 30 communicating with said pump, an auxiliary reservoir located above the level of the discharge of the pump, a by-pass connecting said pipe and reservoir, and an overflow pipe leading from said tank and communicating with the source of fuel supply.

3. In an oil burning system of the type described, in combination with a main source of liquid fuel, means, including a pump, for withdrawing fuel from said source and delivering it to a point of combustion, a valve-controlled by-pass communicating with the

discharge end of the pump, an auxiliary reservoir connected with said by-pass and located above the level of the discharge of the pump, and an overflow conduit leading from 45 said auxiliary reservoir to the main source of fuel supply.

4. In an oil burning system in which oil is withdrawn by a pump from a source located below the level of the pump and delivered to a point of combustion, the method of maintaining the prime in the pump which consists in diverting a portion of the oil delivered by the pump and storing the same 50 above the suction line of the pump, and maintaining constant communication between the stored oil and the pump.

5. In an oil burning system, the method which consists in pumping oil from a source, and continuously delivering a portion of the 55 pumped oil to a point of combustion and a portion to a point of storage located above the level of the suction line of the pump, and preserving the prime in the pump by maintaining communication between the stored 60 liquid and the pump at all times.

6. In a pumping system involving a source of liquid supply and a pump located above the liquid supply and having a suction pipe running to said liquid supply for withdrawing liquid therefrom and delivering it, an auxiliary reservoir of liquid located above the level of the suction pipe running to the liquid supply and of the discharge outlet of 70 said pump and communicating therewith, 75 whereby to maintain liquid in the liquid line and pump when the latter is not in operation.

In testimony whereof I have hereunto set my hand.

LEWIS L. SCOTT.
